UNITED STATES PATENT OFFICE.

EUGENE PIERRE OCTAVER TRUDEL AND AUGUSTE ZIANI, OF MONTREAL, QUEBEC,
CANADA.

ATTACHMENT FOR PUMPS.

1,334,330.

Specification of Letters Patent. Patented Mar. 23, 1920.

Application filed April 2, 1919. Serial No. 287,034.

To all whom it may concern:

Be it known that we, EUGENE PIERRE OCTAVER TRUDEL and AUGUSTE ZIANI, respectively a subject of the King of Great Britain and a citizen of the French Republic, residing at Montreal, Province of Quebec, Dominion of Canada, have invented certain new and useful Improvements in Attachments for Pumps; and we do hereby declare 10 that the following is a full, clear, and exact description of the same.

The present invention relates to improvements in attachments for pumps or the like, and the main object of the invention is to 15 device a simple and effective means to automatically stop a pump when a certain level of fluid has been obtained in a tank.

The device herein disclosed is adapted to shift the driving belt of the pump from the 20 fast to the loose pulley, or to cut out the electric current actuating the operating motor of the pump.

The invention consists essentially in devising an arrangement of parts whereby a 25 float by rising or falling inside a tank will operate a controller bar which, in turn, acts to shift the belt or throw the motor switch as the case may be.

The invention will be better understood 30 with the aid of the accompanying drawings in which:

Figure 1 is a front elevation of the attachment in which the tank is shown in section to disclose the inner arrangement.

Fig. 2 is an enlarged front elevation of the operating attachment.

Fig. 3 is a fragmental detail view of a modified arrangement in which the invention is utilized to operate the switch of an 40 electric motor in the event of the pump being directly connected to the motor.

Like numerals of reference indicate corresponding parts of each figure.

In the drawings, 1 represents a tank having at one end a water inlet pipe 2, and 3 is a bracket on the upper end of said tank in which is suitably journaled a pulley 4, 5 and 6 are pulleys suitably secured in the bottom of said tank, and 7 is a pulley secured to the inner side of said tank adjacent its upper edge.

At any convenient place, near or away from said tank may be secured a base board 8 which is provided with the pulleys 9 and 10, and 11 is a cable adapted to pass over

said pulleys 4, 9, 10, 7, 6 and 5, said cable being secured at one end to the top of a float 12 having depending sides 13, preferably of inverted cup shape, and provided at its top with an air chamber 14. The other end of 60 said cable 11 is secured to the upper member 15 of a toggle, said member 15 being provided with a longitudinal slot 16 in which works a pin 17 secured to the board 8, one end of said member 15 being provided 65 with a hook like or curved portion 18 having a hole 19 therein. The lower member 20 of the toggle is pivotally secured to the lower end of the upper member 15 by means of the pin 21 and has at its other end a 70 hook-like or curved portion 22 in which is provided a central hole 23, and 24 is a spiral spring loosely secured at opposite ends in the holes 19 and 23 to normally hold the toggle members in vertical position. The lower 75 end of said member 20 is pivotally secured on the pin 25 on the base-board 8, and 26 is a horizontally disposed controller bar intermediate of said members 15 and 20, and provided with a longitudinal slot 27 which is 80 adapted to engage the pin 21. At one end of said bar 26 is pivotally connected a link 28 which is adapted to pass through a bracket 29 secured to the base-board 8. The link 28 is provided with two downward depending lugs 30 adapted to engage the driving 85 belt of the pump.

A cable 31 is suitably secured at one end to the bottom of the air chamber 14 of the float and passes around the pulleys 5, 6, and 7, 90 said cable being secured at its other end to the toggle member 15 on the opposite side of the cable 11 so as to exert an opposite pulling action.

It will readily be seen from the foregoing 95 description that immediately on lowering or rising of the water level in the tank 1 according to the manner in which the device has been adjusted, the cables 11 or 31 will exert a pulling action on the toggle due to 100 the upward or downward movement of the float which follows the water level. According to the drawings the device is so arranged that if the water level drops in the tank 1 the float will naturally exert a pulling action on the cable 11 which will naturally pull the toggle 15, 20 gradually or suddenly as the case may be past the vertical position into the dotted line position disclosed in Figs. 1 and 2 of the drawings 110

thereby shifting the controller bar 26 and link 28 toward the right. The lugs 30 which engage the belt will carry the same onto the driving pulley, thereby putting the pump into operation and thus filling the tank to the required level.

The float which will gradually rise with the liquid in the tank will exert a contrary action on the cables, that is: the cable 31 10 will be pulled back carrying with it the toggle 15, 20 and bar 26 which will shift the driving belt onto the loose pulley when the predetermined level has been reached.

In Fig. 3 of the drawings is illustrated a 15 modification of the invention, according to which an electric switch 32, which controls the supply of current to the motor, is actuated by the movements of the controller bar 28, the handle of which is pivotally connected 20 to the bar 28 by means of the link 33. In this case, the pump is connected directly to the motor and no driving belt is used.

34 and 35 are weights provided on the 25 cables 11 and 31 for taking up the slack of said cables and thus imparting an immediate action on the member 15.

It will readily be understood that the construction of this device may be altered or modified according to the existing conditions 30 without departing from the scope and spirit of the invention. It is evident that the device can be easily adapted for other purposes than those specified in the foregoing description.

35. What we claim as our invention is:

1. In a device of the character described, the combination of a toggle comprising a pair of pivotally connected and supported members; a movable controller pivotally connected to the confronting inner ends of said members to be shifted thereby; a tension spring connected at opposite ends to the outer ends of said members; and means distinct from said controller for exerting a direct pulling action upon said members against the tension of said spring to operate the toggle.

2. In a device of the character described, the combination of a toggle comprising a pair of pivotally connected and supported members; an endwise-movable controller bar pivotally connected at one end to the confronting inner ends of said members to be

shifted thereby; a tension spring connected at opposite ends to the outer ends of said members; and means distinct from said bar for pulling said members in either direction against the tension of said spring to operate the toggle.

3. In a device of the character described, the combination of a toggle, upper and lower members and a pivot pin connecting their confronting inner ends, the upper member having a longitudinal slot; a movable controller having a longitudinal slot in which said pin works; upper and lower pins pivotally supporting the outer ends of the respective toggle members, the upper pin projecting through the slot in the upper toggle member; a tension spring connected at opposite ends to the said outer ends of the toggle-members; and means for pulling said toggle members to one side so as to operate said controller.

4. In a device of the character described, the combination of a tank and means for supplying fluid thereto; a float in the tank; a toggle mounted adjacent the tank; a controller for the fluid-supplying means connected to said toggle to be operated thereby; and flexible connecting means between said toggle and said float at opposite sides thereof to operate the former and thereby the controller consequent upon the rising and falling movements of the float due to variations in the level of the fluid in the tank.

5. In a device of the character described, the combination of a tank and means for supplying fluid thereto; a float in the tank; a toggle mounted adjacent the tank; an endwise-movable bar for controlling the fluid-supplying means connected at one end to the toggle to be operated thereby; and cable connections between said toggle and said float to operate the former and thereby shift the controller bar consequent upon the rising and falling movements of the float due to variations in the level of the fluid in the tank.

Signed at Montreal, Quebec, Canada, this 100th day of March, 1919.

EUGENE PIERRE OCTAIVE TRUDEL.
AUGUSTE ZIANI.
